UNITED STATES PATENT OFFICE

AIR VENT AND CLEANER THEREFOR

Sisto V. Sapien, Yakima, Wash.

Application June 1, 1951 Serial No. 239441

Application June 1, 2018 **3 Claims.** **1 Drawing.**

This invention relates to paint sprayers, and more particularly to an air vent attachment for paint sprayers.

A main object of the invention is to provide a novel and improved self-cleaning air vent attachment for use on paint sprayers, said attachment being simple in construction, being easy to install, and involving only a few parts.

A further object of the invention is to provide an improved self-cleaning air vent attachment for use on the paint receptacle of a paint spraying machine, said attachment being inexpensive to manufacture, being sturdy in construction, being easy to remove for cleaning or repair, and requiring no extensive modification of a spraying apparatus on which it is to be employed.

Further objects and advantages of the invention will become apparent from the following description and claims, and from the accompanying drawings, wherein:

Figure 1 is a horizontal, cross-sectional view taken through the spray hose of a paint-spraying apparatus and showing the top wall of the paint container of the apparatus in plan view, and further showing an improved self-cleaning air vent attachment according to the present invention mounted on said top wall;

Figure 2 is a fragmentary side elevational view of the top portion of the paint container of the spraying apparatus of Figure 1, showing the improved self-cleaning air vent attachment of the present invention;

Figure 3 is an enlarged, cross-sectional view taken on the line 3-3 of Figure 1;

Figure 4 is a cross-sectional detail view taken on the line 4-4 of Figure 3;

Figure 5 is a prospective view of a tool suitable for removing the air vent attachment from the paint container of the spraying apparatus when desired;

Figure 6 is a perspective view of the block element and the yoke member movably secured thereto, forming part of the improved self-cleaning air vent attachment shown in Figures 1 to 4.

Referring to the drawings, 11 designates the paint container of the conventional paint-spraying apparatus, and 12 designates the removable top cover or wall of the container. 13 designates the conduit leading to the spray nozzle of the apparatus. Designated at 14 is a hollow stud member which is formed at its top end with a transverse bore 15 communicating with the internal, vertical bore 16 of the stud member, as shown in Figure 3. The stud member is open

at its bottom and is longitudinally notched at 17 to define a plurality of resilient fingers 18 which normally flare outwardly and downwardly, as viewed in Figures 3 and 4. The hollow 5 stud 14 is secured in the wall 12 by being inserted through an opening 19 formed in said wall, the stud being locked in said opening by the expansion of the resilient fingers 18 after the stud has been inserted into the wall to the 10 position shown in Figures 3 and 4.

The top end of the stud 14 is formed with the outwardly divergent, horizontal lugs 20, 20. Designated at 21 is a block member located adjacent the stud 14 and secured at its corner portions to the ends of the lugs 20, 20 by respective machine screws 22, 22, as shown in Figures 1 15 and 4. Rigidly secured to the respective end portions of the block 21 are the parallel rod elements 23, 23, said rod elements extending 20 parallel to the bore 15 in the top end of stud 14, and being arranged symmetrically on opposite sides of said stud. Designated at 24 is a yoke member which is slidably mounted on the rod elements 23, 23 for movement toward and away 25 from the stud 14. Respective coil springs 25, 25 are mounted on the rod elements 23, 23 between the block 21 and the yoke 24, said springs biasing the yoke 24 away from the stud 14. The yoke 24 is retained on the rod elements 23, 23 by the provision of respective cotter pins 26, 26 on the ends of the rod elements 23. Secured to 30 the intermediate portion of the yoke member 24 is a pin member 27 which is located in alignment with the bore 15 and which is normally maintained outside of the bore by the biasing action of springs 25, 25. The yoke member 24 is formed at its central portion with an upstanding finger-engaging lug 28 which the operator of the spray apparatus may employ for 35 pushing the yoke member 24 toward the stud 14, whereby the pin member 27 may be pushed into the bore 15 to clear said bore of dirt, excess paint or the like. During use of the device, the coil springs 25, 25 maintain the pin element 27 out of bore 15, whereby air may freely enter 40 the container 11 through the air passage defined by bore 15 and the internal bore 16 of the stud 14. When it is desired to clear the bore 15, the operator merely pushes the yoke 24 inwardly by 45 means of the finger tab 28, whereby bore 15 may be readily cleared of dirt or other undesired material.

When it is desired to remove the stud 14 from the cover 12, a suitable tool, such as shown at 50 30 in Figure 5, may be employed. The tool 30

comprises a shank 31 formed at one end with a right-angled projection 32, and formed at its other end with a ring 33 which may be grasped by the user. To extract the stud 14, the projection 32 is engaged in the bore 15 and the stud 14 is extracted by pulling upwardly on the ring 33.

While a specific embodiment of an improved self-cleaning air vent attachment for paint sprayers has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A self-cleaning air vent attachment for paint sprayers comprising a hollow stud member formed at its top end with a transverse bore communicating with the interior of the stud member, said stud member being open at its bottom and being adapted to be mounted in the upper wall portion of a paint sprayer to define an air vent therefor, a yoke member movably secured to said stud member, a pin element rigidly carried by said yoke member in alignment with said bore, said yoke member being movable along the axis of the pin element to allow the pin element to enter the bore, and spring means biasing said yoke member away from the stud member toward a position wherein the pin element is outside said bore.

2. A self-cleaning air vent attachment for paint sprayers comprising a hollow stud member formed at its top end with a transverse bore communicating with the interior of the stud member, said stud member being open at its bottom and

being adapted to be mounted in the upper wall portion of a paint sprayer to define an air vent therefor, a transversely extending block element secured to the top end of said stud member, a yoke member movably secured to said block element and disposed opposite therefrom with respect to the stud member, a pin element rigidly carried by said yoke member in alignment with said bore, said yoke member being movable along the axis of the pin element to allow the pin element to enter the bore, and spring means biasing said yoke member away from the stud member toward a position wherein the pin element is outside said bore.

3. A self-cleaning air vent attachment for paint sprayers comprising a hollow stud member formed at its top end with a transverse bore communicating with the interior of the stud member, said stud member being open at its bottom and being adapted to be mounted in the upper wall portion of a paint sprayer to define an air vent therefor, a transversely extending block element secured to the top end of said stud member, a pair of parallel arms secured to said block element on opposite sides of said stud member and extending parallel to said bore, a yoke member slidably mounted on said arms, a pin element rigidly carried by said yoke member in alignment with said bore, said yoke member being movable along said arms to allow the pin element to enter the bore, and spring means biasing said yoke member away from the stud member toward a position wherein the pin element is outside said bore.
